(57) **CLAIM**

The ornamental design for a valve, as shown and described.

DESCRIPTION

FIG. 1 is a top view of the one touch valve of the present invention;

FIG. 2 is a bottom view of the one touch valve of the present invention;

FIG. 3 is a front view of the one touch valve of the present invention;

FIG. 4 is a rear view of the one touch valve of the present invention;

FIG. 5 is a left view of the one touch valve of the present invention; and,

FIG. 6 is a right view of the one touch valve of the present invention.

In the drawings, the broken lines represent environmental structure forming no part of the claimed design.
